UNITED STATES PATENT OFFICE.

NILS H. ANDERSON, OF BRIDGEPORT, CONNECTICUT, ASSIGNOR, BY DIRECT AND MESNE ASSIGNMENTS, TO UNDERWOOD TYPEWRITER COMPANY, OF NEW YORK, N. Y., A CORPORATION OF DELAWARE.

SOUND AND SHOCK ABSORBING MACHINE-SUPPORT.

1,356,182.

Specification of Letters Patent. Patented Oct. 19, 1920.

Application filed May 16, 1918, Serial No. 234,861. Renewed March 16, 1920. Serial No. 366,300.

To all whom it may concern:

Be it known that I, NILS H. ANDERSON, a citizen of the United States, residing at Bridgeport, in the county of Fairfield and State of Connecticut, have invented a new and useful Improvement in Sound and Shock Absorbing Machine-Supports, of which the following is a specification.

This invention relates to the construction of sound and shock absorbing supports or cushion feet for supporting machinery in general, and that are particularly serviceable for sustaining typewriters, calculating machines, cash registers and similar key actuated machines which it is desirable to have operate as smoothly and noiselessly as possible.

An object of the present invention is to simplify and cheapen the manufacture of such supports, increase their efficiency as sound and shock absorbing devices, and facilitate their attachment to the machines with which they are to be used.

Figure 1 of the accompanying drawings shows a side elevation of a foot which embodies this invention, attached to a machine frame and fastened by a clamp to the top of a table or desk or to the floor. Fig. 2 shows a vertical section of the same. Fig. 3 illustrates, on a larger scale, a vertical section of the foot attached to a machine frame, showing the shape of the cushion and its relation to the attachment stud before being subjected to the weight of the machine. Fig. 4 is a similar view showing the relation of the parts when sustaining the full weight of the machine and the downward pressure incident to the use of the machine. Fig. 5 shows a horizontal section on the plane indicated by the dotted line 5—5 on Fig. 2. Fig. 6 shows an elevation looking in the direction of the arrow on Fig. 2.

The attachment stud 10 of the foot has a threaded stem 11 which is adapted to be screwed into a threaded socket 12 in the frame 13 of a writing, calculating, recording or other machine. The head 14 of the attachment stud has a flange 15 and below the flange it is of conoidal form, or curved inwardly from the flange toward the smaller lower end which is provided with a slot 16 suitable for the application of a screwdriver.

The cushion 17, which is preferably made

of yielding rubber, has a central longitudinal opening 18 from bottom to top. The wall of the lower portion of the opening through the cushion is shaped to receive and fit the lower end of the head of the attachment stud, while the wall of the upper portion of this opening is curved outwardly on a radius somewhat less than the radius of the curved part of the head of the attachment stud which it receives. With this construction the head of the attachment stud settles down into the opening in the cushion more or less according to the weight of the machine, and as the downward force increases, due to added weight of the machine or to the operation of the machine, the area of the curved wall of the opening through the cushion in contact with the curved wall of the head of the stud increases and offers added resistance to this downward force or pressure. It is preferred to have the curve of the wall of the stud head and the wall of the opening through the cushion so related that when subjected to the full effect of the downward pressure the upper part of the stud does not completely fill the upper part of the opening through the cushion. This construction insures a more sensitive seat or delicate balance for the machine than if the stud closely fitted the opening through the cushion, and it results in a complete absorption of shock and sound when the machine is being operated.

The cushion is encased in a metal protecting and attaching shell 19. The upper end 20 of this shell is bent inward over the flange of the head of the attachment stud, so that the shell may move up and down but cannot drop off the stud when the machine is moved. The lower end 22 of the shell is spun inward over a shoulder on the cushion and above the inwardly bent lower end the shell preferably has an interior annular groove or recess 21. The yielding cushion when inserted into the shell extends into this groove or recess and is thereby retained in place. Having the stud opening extend completely through the cushion permits the ready application of a screwdriver to the slot in the head of the stud for screwing it into or out of place, and it also enables the cushion to be contracted sufficiently to be easily inserted into the shell.

A sleeve 23 of sound and shock absorbing material may be placed upon the stud above the head, if desired.

A holder 24 may be provided for receiving the lower end of the shell of this foot, and this holder may have a flange 25 by which it may be fastened to the top of a desk or table or to the floor. A screw 26 is threaded through the wall of the holder so that its end may be set against the shoulder on the shell, as shown in Fig. 2. When used with a typewriter two of these holders may be located to receive feet at the front of the machine, and when the screws 26 are loosened the machine is free to be removed from a desk or table.

The invention claimed is;

1. A sound-eliminating and shock-absorbing machine support comprising, in combination, a stud having a body portion terminating at its upper end in a part adapted to be attached to a machine to be supported and at its lower end in a head of conoidal form relatively large at the top and small 25 at the bottom, a resilient cushion having an opening therethrough, the upper portion of said opening being also of conoidal form and larger at the top than at the bottom, to receive the conoidal portion of said head 30 as a bearing element, and an integral annular confining-band surrounding said cushion but leaving an exposed bearing portion at the bottom, said band and cushion being provided with mutually interengaging parts 35 when assembled to maintain said cushion in place, and said band and stud having mutually interengageable elements capable of permitting limited movement therebetween, but serving to prevent accidental separation 40 of one from the other.

2. A sound-eliminating and shock-absorbing machine support comprising, in combination, a stud having a body portion terminating at its upper end in a part adapted 45 to be attached to a machine to be supported and at its lower end in a head of conoidal form relatively large at the top and small at the bottom, the top of said head being of greater diameter than the adjoining portion 50 of said stud, so as to form a retaining shoulder, a resilient cushion having an opening therethrough, the upper portion of said opening being also of conoidal form and larger at the top than at the bottom, to receive the conoidal portion of said head as a bearing element, and an integral annular confining-band surrounding said cushion but

leaving an exposed bearing portion at the bottom, said band and cushion being provided with mutually interengaging parts 60 when assembled to maintain said cushion in place, and said band having an inwardly disposed retaining flange of smaller internal diameter than that of the retaining shoulder formed by the top of said head 65 and capable of coöperating therewith to permit limited relative movement between said stud and said band, but serving to prevent accidental separation of one from the other. 70

3. A sound-eliminating and shock-absorbing machine support comprising, in combination, a stud having a body portion terminating at its upper end in a part adapted to be attached to a machine to be supported 75 and at its lower end in a head of conoidal form relatively large at the top and small at the bottom, a resilient cushion having an opening therethrough, the upper portion of said opening being also of conoidal form 80 and larger at the top than at the bottom, to receive the conoidal portion of said head as a bearing element, and an integral annular confining band surrounding said cushion but leaving an exposed bearing portion at 85 the bottom, said band being provided with an inwardly disposed annular recessed portion and said cushion having an annular enlargement to engage with said recessed portion to normally maintain said band and 90 cushion in interlocked relation, and said band and stud having mutually interengageable elements capable of permitting limited movement therebetween, but serving to prevent accidental separation of one from 95 the other.

4. A sound-eliminating and shock-absorbing machine support comprising a resilient cushion, means for securing said cushion to the machine to be supported, said securing 100 means comprising a stud having a head to transmit the weight to be supported to said cushion, a restraining-band to prevent outward expansion of said cushion when compressed, the stud, band, and cushion having 105 relatively interengageable parts serving to confine said cushion in said band and permit limited relative movement between said band and stud, but preventing accidental separation thereof, a standard adapted to be 110 firmly secured to a supporting surface, and means for clamping said restraining band securely in said standard.
